UNITED STATES PATENT OFFICE.

JOHN N. SELVIG, OF CHICAGO, ILLINOIS.

METHOD OF AND APPARATUS FOR TREATING FIBROUS MATERIAL.

Application filed September 27, 1922. Serial No. 590,862.

My invention relates to method of and apparatus for treating fibrous material, and more particularly to the breaking and scutching of fibrous material such as hemp, sisal grass, flax and other fiber producing materials.

One of the objects of my invention is the provision of apparatus of simple and inexpensive construction, which may be readily operated by a person unskilled in mechanics, and which will effectively break into short pieces the woody content of the material and then scutch the material to remove the broken woody pieces therefrom without breaking, weakening or otherwise injuring the fiber.

A more specific object of my invention is the provision of apparatus so constructed that the fibrous material is bent at certain places in one direction and then bent in the opposite direction, preferably at substantially the same places, to insure completely breaking the woody substance of the material; and, to this end, my invention preferably contemplates the combination of a normally stationary bar over which the material to be treated is fed, rotating means including a set of beater bars arranged to pass the adjacent edge of said bar and to bend the material at certain places thereover in one direction, and means rotating oppositely with respect to said first mentioned rotating means and also including a set of beater bars which are adapted to pass the adjacent edges of the respective first mentioned beater bars and to bend the material over said edges at substantially the same places but in the opposite direction.

Fibrous materials absorb a considerable amount of moisture and, when they are in a damp condition, because of their inherent, tough, yielding characteristics, it is much more difficult to break the woody substances thereof than is the case when the materials are in a dry condition. I have found, however, when the ends of the material are bent first in one direction and then in the opposite direction through angles substantially more than ninety degrees, and particularly when the second bend occurs at substantially the same place as the first bend, that the woody content of the material, even when the material is in a damp condition, is effectively broken and at the same time the fiber is well loosened on the pieces of woody material so it may be easily scurched there-

from. It is a further object of my invention, therefore, to provide apparatus so constructed that it will bend the material in the manner described; and, to this end, preferably, the stationary bar is tangentially positioned with respect to the orbital path traveled by the first set of beater bars and the side of said stationary bar adjacent thereto is under-beveled while the respective edges of the upper beater bars are also under-beveled.

It is a further object of my invention to provide an apparatus so constructed that it will operate with a minimum amount of power and without being subjected to any severe strains or stresses; and this object is preferably accomplished by arranging the beater bars of the first set spirally so that the stalks of the fibrous material lying side by side across the stationary bar are successively attacked by each of the beater bars, the beater bars of the second set being also oppositely spiralled with respect to the respective beater bars of the first set so that the stalks of the fibrous material are again successively attacked by each of the second mentioned beater bars.

A further object of my invention is the provision of a pair of rotatable feed rollers adjacent the rear side of the stationary bar, one of said rollers preferably being yieldably supported relative to the other, which are driven at such speeds that the material is fed over the forward edge of the stationary bar at a predetermined rate with respect to the rotative speeds of the respective sets of beater bars, being held by said rollers while the woody content of the material is progressively broken into pieces of the desired length and is scurched from the fibers of the material.

A further object of my invention is the provision of means, preferably in the form of a bar floatingly supported over the stationary bar, whereby the short ends of the stalks of fibrous material after leaving the feed rollers will be held until the extremities of the stalks approach quite closely the forward edge of the stationary bar over which they are broken, thus subjecting substantially the entire lengths of the stalks of material to the bending, breaking and scurching actions of the beater bars.

It is a further object of my invention to provide an apparatus so constructed that it will not only effectively break the woody

content of the material into short pieces, but will also effectively separate or scutch the woody pieces from the fiber immediately after the breaking occurs and before the woody pieces become entangled with the fiber. In this connection my invention contemplates the provision of an apparatus preferably so constructed that the material is scutched by the first set of beater bars on one side and then on the other side by those of the second set; the first set of bars are so arranged relative to the respective bars of the second set that the fiber is stretched rather taut across the respective edges of the bars of the first set and the co-operating edges of the bars of the second set, while the short lengths of woody matter are rocked on the respective edges of the bars of the second set, the rear ends being pushed between the strands of fiber by the respective bars of the first set to such an extent that the woody pieces are effectively loosened from the fiber and a considerable part of the woody matter is separated from the fiber at this point. Any woody pieces remaining in the fiber are scutched out by the beater bars of the second set, this being accomplished preferably by rotating the two sets of beater bars in opposite directions but at the same rotative speed and causing the bars of the second set to travel at a peripheral speed greater than that of the bars of the first set, for example, by providing supporting means for the second set of bars of greater radii than those of the means supporting the first set of bars. Since the material is held by the feed rollers, the floating bar, or by both the feed rollers and the floating bar and is drawn around rather taut over the forward edge of the stationary bar and then over the respective edges of the beater bars of the first set and the woody content thereof has been broken into short pieces and loosened from the fiber, it will be apparent, when the beater bars of the second set travel at a relatively higher peripheral speed, that said beater bars upon leaving the respective bars of the first set will readily scutch and separate from the fiber any woody matter remaining therein. It is a further object of my invention to provide means whereby the apparatus may be readily adjusted so that it will handle fibrous material either fine or coarse or, when the material being treated is more or less frail, it may be adjusted so that such material may be handled less severely and the woody matter broken and separated from the fiber without placing the latter under any severe strain; and, to this end, preferably the stationary bar over which the material is fed is made adjustable relative to the first set of beater bars, so that said bar may be moved away from or toward the path traveled by said bars, and the beater bars of the second set are arranged to be adjusted

angularly relative to the driving means for the shaft on which they are mounted so that the desired clearances may be obtained between the bars of the second set and the respective bars of the first set.

The beater bars travel at a considerable speed and vacuous pockets form behind the respective bars. The fiber after the woody matter has been removed therefrom, is light and there is a considerable tendency for the fiber to be drawn into the orbital paths of the respective sets of beater bars, thus becoming injured and interfering with the operation of the apparatus. It is a further object of my invention to provide means so arranged that this is prevented and the fiber is maintained in the intended path through the machine.

The invention consists in the novel constructions, arrangements and devices to be hereinafter described and claimed for carrying out the above stated objects and such other objects as will appear from the following specification, and it consists further in the improved method of treating fibrous material to be hereinafter described and claimed.

The invention is illustrated in certain preferred embodiments in the accompanying drawings, wherein—

Fig. 1 is an elevational view of one side of an apparatus embodying the principles of my invention, certain parts thereof being broken away;

Fig. 2 is an elevational view of the opposite side of the apparatus;

Fig. 3 is a plan view, on an enlarged scale, of the apparatus, the cover or housing thereof having been removed and certain parts of the apparatus broken out;

Fig. 4 is a sectional view taken on the line 4—4 of Fig. 3;

Fig. 5 is a sectional view taken on the line 5—5 of Fig. 3; showing the means whereby the second set of beater bars may be angularly adjusted relative to the driving and supporting shaft therefor;

Fig. 6 is a side elevational view of the parts shown in Fig. 5; and

Figs. 7, 8 and 9 are diagrammatic views showing the relative positions of the beater bars and the horizontal stationary bar during the bending and scutching of the material.

Like characters of reference designate like parts in the several views.

Referring now to the drawings, the apparatus is supported in a framework including two longitudinally extending frame members 12 held in spaced relation by transversely extending members 13, 14 and 15, said framework being placed on a sub-frame 16 which is supported by a plurality of legs 17.

The upper end of the frame member 15 is

provided with an angularly positioned flange 18. A feed roller 19, journaled in the side frame members 12, is positioned just ahead of the flange 18. A normally stationary bar 20 is positioned ahead of the roller 19, being secured to the respective side frame members 12 by cap screws 21. The bar 20 is provided with transversely extending slots 22 through which the cap screws 21 extend so that said bar may be adjusted relative to the frame members 12. A pair of arms 23 are pivotally connected at their forward ends to the respective side frame members 12. A feed roller 24, adapted to cooperate with the roller 19, is journaled in the arms 23. Vertically extending rods 25 having their upper ends hooked over the rear ends of the respective arms 23 extend through brackets 26 which form a part of, or are rigidly secured to, the transverse frame member 15. Washers 27 are slipped over the lower ends of the rods 25 and are prevented from slipping off by nuts 28. Springs 29 are coiled about the rods 25, being interposed between the undersides of the brackets 26 and the upper sides of the washers 27, respectively. The upper feed roller 24, therefore, is yieldingly supported relative to the roller 19, being normally pulled down toward the roller 19. A trough 30 is attached to the rear end of the machine in such manner that the material to be treated may be fed therefrom to the rollers 19 and 24.

A shaft 31 is journaled in the frame members 12 and is provided with a pulley 32, said shaft being connected to a suitable source of power, for example, a motor 33 by a belt 34 trained over said pulley and the pulley of the motor. A pair of spiders 35 are fixed to the shaft 31 and support the beater bars 36, said spiders being angularly displaced relative to each other so that the beater bars are spirally arranged substantially as shown in Figs. 3 and 4. A shaft 37 is also journaled in the side frame members 12 and is driven from and at the same speed as the shaft 31 by gears 38 and 39 fixed to said respective shafts, the shaft 31 being driven in an anti-clockwise direction, and the shaft 37 in a clockwise direction, as viewed in Fig. 4. A pair of spiders 40 are fixed to the shaft 37 and support the beater bars 41, said spiders being angularly displaced relative to each other so that the beater bars are spirally arranged but oppositely with respect to the beater bars 36.

On one side of the apparatus a sprocket wheel 42 is fixed to the shaft 31 and a sprocket wheel 43 is fixed to the roller 24, said sprocket wheels being connected by a chain 44. On the opposite side of the machine a sprocket wheel 45 is fixed to the shaft 37 and a sprocket wheel 46 is fixed to the roller 19, said sprocket wheels being connected by a chain 47. The rollers 19 and 24, therefore, rotate in the same direction as the shafts 37 and 31, respectively.

The gear 38 is split circumferentially, the hub portion 38^a, and the rim portion 38^b thereof being connected by bolts 48. The rim portion 38^b is provided with circumferentially extending slots 49 through which said bolts are inserted so that it may be adjusted angularly with respect to the hub portion, the latter being fixed to the shaft 37 in any desired manner.

A bar 50 is floatingly supported over the stationary bar 20, being attached to the forward ends of a pair of arms 51 which are pivotally connected at their rear ends to the respective arms 23.

The fiber may be carried away by a conveyor 52 extending over suitable rollers 53 and 54 fixed to shafts 55 and 56, respectively, which are journaled in the side members 12. The shaft 56 is provided with a sprocket 57 and the shaft 37 is provided with a sprocket 58, a chain 59 extending over said sprockets to drive the conveyor. The top of the apparatus may be closed by a hinged cover 60. The bottom of the apparatus is provided with a hopper 61 having an outlet 62 through which the pieces of woody matter after being separated from the fiber may drop.

Transversely extending nozzles 63 and 64 are tangentially disposed relative to the respective orbital paths traveled by the beater bars 36 and 41, see Fig. 4, these nozzles being connected by pipes 65 and 66 with a blower 67, the latter being operatively connected with the motor 33.

Operation.—The material to be treated is placed in the feed trough 30 and moved forwardly until it is caught by the feed rollers 19 and 24. The feed rollers are preferably small in diameter so they will substantially flatten the stalks of material and prepare them for the bending operations to follow. The feed rollers push the stalks of material forwardly over the stationary bar 20 and under the floating bar 50. Assuming the woody substances of the stalks are to be broken at points an inch apart and that one of the beater bars 36 is just leaving the working edge of the stationary bar 20, the driving means for the feed rollers is such that said rollers are operated at a speed sufficient to advance the stalks of material one inch over the working edge of the stationary bar 20 before they are attacked by the next following beater bar. In the case assumed, the location of the shaft 37 and the radii of the spiders 40 are such that the orbital path traveled by the working edges of the beater bars 41 is substantially one inch from the working edge of the stationary bar 20, also the first and second set of beater bars are so arranged and rotated with relation to each other so that the stalks of material will be bent at the same point by the two sets of beater bars.

other that the working edge of one of the bars 36 will have traveled a distance of substantially one inch, away from the working edge of the bar 20, before the working edge 6 of the co-operating bar 41 begins to move across the working edge of said bar 36.

The stalks of material lying side by side with their free ends progressively advanced over the working edge of the stationary bar 10 20 are successively attacked by each of the spirally arranged beater bars 36 and are bent, at certain places, namely, at the places just over the working edge of the bar 20, downwardly over that edge of said bar 20; 15 and, in a like manner, the stalks of material are then successively attacked by each of the beater bars 41 and are bent, at substantially the same places, upwardly over the working edges of the respective beater bars 36.

20 The relative positions of the beater bars 36 and 41 with respect to each other and with respect to the stationary bar 20 during the bending of the material are illustrated diagrammatically in Figs. 7, 8 and 9. 25 Referring to Figs. 4 and 7, it will be noted that the bar 20 is tangentially disposed relative to the orbital path traveled by the beater bars 36 and also that its side 20^a is under-beveled. It will also be noted from 30 Figs. 4 and 8 that the respective beater bars 36 are also under-beveled at 36^a. The orbital path traveled by the beater bars 36 relative to the stationary bar 20 is such that the ends of the stalks are bent around 35 through an angle substantially more than ninety degrees; in the apparatus shown in the drawings, the free ends of the material are carried around through an angle of substantially one hundred and twenty degrees, 40 see Fig. 7. The orbital path traveled by the beater bars 41 with respect to the orbital path traveled by the beater bars 36 is such that the free ends of the material are not only bent over the working edges 45 of the respective beater bars 36 at substantially the same places but they are carried through an angle substantially more than ninety degrees in the opposite direction, the angle through which the ends of 50 the material are carried by the beater bars 41, in the apparatus shown, being also substantially one hundred and twenty degrees, see Fig. 8. This arrangement insures a 55 complete break of the woody content of the stalks even though the material contain considerable moisture and be in a damp condition and it also insures the fibers being effectively loosened from both sides of the broken off pieces of woody matter.

60 The bending and scutching operations performed on the material will best be understood by reference to Figs. 7, 8 and 9. In Fig. 7 a stalk of material is shown as having been attacked at the points x, y and z by the beater bars 36 and having been attacked

at the point x by one of the beater bars 41, the woody piece a being shown as completely broken off and the woody pieces b and c as partially broken off. Taking up the operations on the stalk at this point—the beater bar 36 continues traveling downwardly, as shown by the arrows, and the beater bar 41 moves across the working edge of the bar 36, as shown by the arrows, substantially into the positions shown in Fig. 8, which causes the piece b to be completely broken off at the point v and to be rocked on the working edge of the bar 41, the rear end of said piece b being pushed downwardly by the working edge of the bar 36 and thus the piece b is torn loose from the fibers which at this time are stretched rather taut down over the working edge of the bar 20 and across the working edges of the bars 36 and 41. The bars 36 and 41 continue advancing 85 in their respective paths and as the bar 41 soon moves clear of the piece b the working edge of the bar 36 scatches on the upper side the fiber holding the piece b, which continues to be drawn more or less taut over the working edges of the bars 20, 36 and 41, with the consequent result that the piece b is forced into a position substantially as shown in 90 Fig. 9. At this point the piece b is likely to be freed from the fiber, in which case it falls into the hopper underneath. The woody piece a is shown still clinging to the fiber, it not having been entirely scutched out by the bar 36, but, since the piece a is only very insecurely held by the fiber and lies 100 directly in front of the bar 41, it is readily freed by the scutching action of said bar which takes place on the under side of the fiber. In the embodiment illustrated in the drawings, the angular speed of the beater bars 41 is the same as that of the beater bars 36. The peripheral speed of the beater bars 41, however, is greater than that of the beater bars 36 because the radii of the arms of the spiders 40 supporting the beater bars 105 41 is made greater than those of the arms of the spiders 35 supporting the beater bars 36. Therefore, after the beater bars 41 cross the respective beater bars 36, the distance between the working edges of said bars 36 and 110 41 progressively increases. This arrangement enables the bar 41 to move clear of the piece b quicker so that said piece is subjected to the full scutching effect of the bar 36. It will be observed that the pieces of woody 115 matter are scutched from the fiber while the fiber is drawn taut and, therefore, the likelihood of the woody pieces becoming entangled in the fiber is reduced to a minimum.

120 It will be noted that the clearance between the lower edge of the surface 20^a of the bar 20 and the orbital path traveled by the beater bars 36 is considerably greater than that between the upper edge of said surface and said path. The clearance be- 125 13

- tween the upper edge of the respective surfaces 36^a of the beater bars 36 and the orbital path traveled by the beater bars 41 is considerably greater than that between the lower edge of said surface and said path. This arrangement relieves the fiber of all unnecessary strains while it is bent and scutched by the respective beater bars. The distance between the respective beater bars 41 and 10 36 increases after the bars 41 pass the respective bars 36 thus increasingly relieving the fiber of all unnecessary strain immediately after the woody matter has been separated from it.
- 15 The floating bar 50 serves to hold the short ends of the stalks of material after they leave the feed rollers 19 and 24 so that the stalks throughout their entire length are subjected to the bending and scutching actions hereinbefore described. The bar 50 also weights the stalks of material down and prevents them from tilting on the bar 20 when attacked by the beater bars 36.
- 20 The bar 20 being adjustable relative to the orbital path traveled by the beater bars 36 and the beater bars 41 being angularly adjustable relative to the beater bars 36, it will be apparent that the apparatus may be readily adjusted to handle either fine or coarse material, or, when the material handled is frail, the parts may be adjusted so that the fiber is not subjected so severely to the bending and scutching operations.
- 25 The beater bars 36 and 41 are operated at a fairly high rate of speed and because of the positions of these respective bars vacuous pockets form behind the bars into which the light fibers are likely to be drawn, consequently causing the fibers to follow and 30 wind on the beater bars which is likely to injure the fibers and also interfere with the operation of the apparatus. By providing the tangentially positioned nozzles 63 and 64 delivering air at a considerable velocity, the vacuous pockets are destroyed and the fibers, under the co-operating action of the air currents from said nozzles, are blown straight out over the conveyor 52 and carried in the intended path of travel uninjured from the apparatus.
- 35 From the foregoing description it will be apparent to those skilled in the art that my apparatus is of simple and inexpensive construction, requiring but a minimum amount of power to operate, and also that it may be operated by persons unskilled in mechanics. It will effectively remove substantially all the woody matter from the fiber without breaking, weakening or otherwise injuring the fiber to any appreciable extent. Furthermore, because of the manner in which the material is bent and scutched it is not necessary to over-ret the material, as is frequently done to enable a larger percentage of the woody content to be removed, con-
- sequently, the cleaned fibers are strong and bring the highest market price.
- I do not intend to limit my invention to the details of construction shown and described, except only in so far as certain of the appended claims are specifically so limited, as it will be obvious that modifications may be made without departing from the principles of my invention.
- I claim:
1. Method of treating fibrous material which consists in bending the material in one direction to effect a breaking action on the woody matter therein, then bending the material at substantially the same place in the 80 opposite direction to complete breaking off the end of said woody matter, and then moving the broken off piece of woody matter relative to the fibers to loosen the hold of the fibers thereon. 75
2. Method of treating fibrous material which consists in bending the material in one direction to effect a breaking action on the woody matter therein, then bending the material at substantially the same place in the 85 opposite direction, one of the bending operations being carried through an angle substantially more than ninety degrees thereby breaking off the end of said woody matter, and then moving the broken off piece of 90 woody matter relative to the fibers to loosen the hold of the fibers thereon. 95
3. Method of treating fibrous material which consists in bending the material at certain places in one direction through an 100 angle substantially more than ninety degrees and then bending it at substantially the same places in the opposite direction through an angle substantially more than ninety degrees, for the purpose specified. 105
4. Method of treating fibrous material which consists in bending the material in one direction to effect a breaking action on the woody matter therein, then bending the material at substantially the same place in the 110 opposite direction to complete breaking off the end of said woody matter, then moving the broken off piece of woody matter relative to the fibers to loosen the hold of the fibers thereon, and then removing the broken off 115 piece of woody matter from the fibers. 115
5. Method of treating fibrous material which consists in bending the material in one direction to effect a breaking action on the woody matter therein, then bending the material at substantially the same place in the 120 opposite direction, one of the bending operations being carried through an angle substantially more than ninety degrees thereby breaking off the end of said woody matter, 125 then moving the broken off piece of woody matter relative to the fibers to loosen the hold of the fibers thereon, and then removing the broken off piece of woody matter from the fibers. 130

6. Method of treating fibrous material which consists in bending the material at certain places in one direction through an angle substantially more than ninety degrees, then bending it at substantially the same places in the opposite direction through an angle substantially more than ninety degrees to break off the woody matter contained therein into short pieces, and then removing the pieces of woody matter therefrom.
7. Method of treating fibrous material which consists in holding the material at one end, bending said material at the other end, first in one direction at certain places to effect a breaking action on the woody matter therein and then at substantially the same places in the opposite direction to complete breaking off the ends of said woody matter, then moving the broken off pieces of woody matter relative to the fibers to loosen the hold of the fibers thereon, and then scutching the material to remove the pieces of woody matter therefrom.
8. Method of treating fibrous material which consists in holding the material at one end, bending said material at the other end, first in one direction to effect a breaking action on the woody matter therein, then bending the material at substantially the same place in the opposite direction, one of the bending operations being carried through an angle substantially more than ninety degrees thereby breaking off the end of said woody matter, then moving the broken off piece of woody matter relative to the fibers to loosen the hold of the fibers thereon, and then scutching the material to remove the piece of woody matter therefrom.
9. Method of treating fibrous material which consists in holding the material at one end, bending said material at the other end first in one direction at certain places through an angle substantially more than ninety degrees and then bending it at substantially the same places in the opposite direction through an angle substantially more than ninety degrees to break off the woody matter contained therein into short pieces, and then scutching the material to remove the pieces of woody matter therefrom.
10. In apparatus for treating fibrous material, the combination of means adapted to bend the material in one direction to effect a breaking action on the woody matter therein, and means adapted to bend the material at substantially the same place in the opposite direction to complete breaking off the end of said woody matter, said last-named means being so arranged that the broken off piece of woody matter is moved relative to the fibers thereby loosening the hold of the fibers thereon.
11. In apparatus for treating fibrous material, the combination of means adapted to bend the material in one direction to effect a breaking action on the woody matter therein, and means adapted to bend the material at substantially the same place in the opposite direction, one of said means being capable of carrying one of the bending operations through an angle substantially more than ninety degrees thereby breaking off the end of said woody matter, said last-named means being so arranged that the broken off piece of woody matter is moved relative to the fibers thereby loosening the hold of the fibers thereon. 70
12. In apparatus for treating fibrous material, the combination of means adapted to bend the material at certain places in one direction through an angle substantially more than ninety degrees, and means adapted to bend it at substantially the same places in the opposite direction through an angle substantially more than ninety degrees, for the purpose specified. 75
13. In apparatus for treating fibrous material, the combination of a bar over which the material may be fed, rotating means including a plurality of beater bars adapted to pass the adjacent edge of said first-named bar and to bend the material thereover in one direction, and means rotating oppositely with respect to said first mentioned rotating means and having a plurality of beater bars adapted to pass relatively close to the adjacent edges of the respective first mentioned beater bars and to bend the material over said edges in the opposite direction, for the purpose specified. 80
14. In apparatus for treating fibrous material, the combination of a stationary bar over which the material may be fed, rotating means including a plurality of beater bars adapted to pass the adjacent edge of said bar, and means rotating oppositely with respect to said first mentioned rotating means and having a plurality of beater bars adapted to pass the adjacent edges of the respective first mentioned beater bars, said stationary bar being so positioned relative to the path traveled by said first mentioned beater bars and said first and second mentioned beater bars being so arranged relative to each other that the free ends of said material are bent over the edge of said stationary bar in one direction through an angle substantially more than ninety degrees and then are bent over the edges of said respective first mentioned beater bars in the opposite direction through an angle substantially more than ninety degrees, for the purpose specified. 85
15. In apparatus for treating fibrous material, the combination of a stationary bar over which the material may be fed, rotating means including a plurality of beater bars

- bars adapted to pass the adjacent edge of said bar, and means rotating oppositely with respect to said first mentioned rotating means and having a plurality of beater bars 5 adapted to pass the adjacent edges of the respective first mentioned beater bars, said stationary bar being so positioned relative to the path traveled by said first mentioned beater bars and said first and second mentioned beater bars being so arranged relative to each other that the free ends of said material at certain places are bent over the edge of said stationary bar in one direction through an angle substantially more than 10 ninety degrees and then are bent over the edges of said respective first mentioned beater bars in the opposite direction at substantially the same places and through an angle substantially more than ninety degrees, for the purpose specified.
16. In apparatus for treating fibrous material, the combination of a stationary bar over which the material may be fed, rotating means including a plurality of beater bars 25 adapted to pass the adjacent side of said bar, said bar being positioned tangentially with respect to the orbital path traveled by said beater bars and having its said side under-beveled, and means rotating oppositely with respect to said first mentioned rotating means and having a plurality of beater bars adapted to pass the adjacent sides of the respective first mentioned beater bars, said sides of said first mentioned beater bars being under-beveled with respect to the orbital path traveled by said second mentioned beater bars, for the purpose specified.
17. In apparatus for treating fibrous material, the combination of a stationary bar over which the material may be fed, rotating means including a plurality of spirally arranged beater bars adapted to pass the adjacent edge of said bar and to bend the material successively thereover in one direction, and means rotating oppositely with respect to said first mentioned rotating means and having a plurality of beater bars spiralled oppositely from the first mentioned beater bars and adapted to pass the adjacent edges of the respective first mentioned beater bars and to bend the material successively over said edges in the opposite direction, for the purpose specified.
18. In apparatus for treating fibrous material, the combination of a stationary bar over which the material may be fed, rotating means including a plurality of spirally arranged beater bars adapted to pass the adjacent edge of said bar and to bend the material successively at certain places thereover in one direction, and means rotating oppositely with respect to said first mentioned rotating means and having a plurality of beater bars spiralled oppositely from one direction, and means rotating oppositely with respect to said first mentioned beater bars and adapted to pass the adjacent edges of the respective first mentioned beater bars and to bend the material successively over said edges in the opposite direction, for the purpose specified.
19. In apparatus for treating fibrous material, the combination of a stationary bar over which the material may be fed, rotating means including a plurality of spirally arranged beater bars adapted to pass the adjacent edge of said bar, and means rotating oppositely with respect to said first mentioned rotating means and having a plurality of beater bars spiralled oppositely from the first mentioned beater bars and adapted to pass the adjacent edges of the respective first mentioned beater bars, said stationary bar being so positioned relative to the path traveled by said first mentioned beater bars and said first and second mentioned beater bars being so arranged relative to each other that the free ends of said material are bent over the edge of said stationary bar successively in one direction through an angle substantially more than ninety degrees and then are bent over the edges of said respective first mentioned beater bars successively in the opposite direction through an angle substantially more than ninety degrees, for the purpose specified.
20. In apparatus for treating fibrous material, the combination of a stationary bar over which the material may be fed, rotating means including a plurality of spirally arranged beater bars adapted to pass the adjacent edge of said bar, and means rotating oppositely with respect to said first mentioned rotating means and having a plurality of beater bars spiralled oppositely from the first mentioned beater bars and adapted to pass the adjacent edges of the respective first mentioned beater bars, said stationary bar being so positioned relative to the path traveled by said first mentioned beater bars and said first and second mentioned beater bars being so arranged relative to each other that the free ends of said material at certain places are bent over the edge of said stationary bar successively in one direction through an angle substantially more than ninety degrees and then are bent over the edges of said respective first mentioned beater bars successively in the opposite direction at substantially the same places and through an angle substantially more than ninety degrees, for the purpose specified.
21. In apparatus for treating fibrous material, the combination of a bar over which the material may be fed, rotating means including a plurality of beater bars adapted to pass the adjacent edge of said first-named bar and to bend the material thereover in one direction, and means rotating oppositely with respect to said first mentioned beater bars and adapted to pass the adjacent edges of the respective first mentioned beater bars and to bend the material successively over said edges in the opposite direction, for the purpose specified.

- with respect to said first-named rotating means and having a plurality of beater bars adapted to pass relatively close to the adjacent edges of the respective first-named beater bars and to bend the material over said edges in the opposite direction, the peripheral speed of one of said sets of beater bars being greater than that of the other set, for the purpose specified. 6 70
- 10 22. In apparatus for treating fibrous material, the combination of means for holding the material, a stationary bar positioned ahead of said holding means over which the material may be fed, rotating means including a set of beater bars adapted to pass the adjacent edge of said bar and to bend the material thereover in one direction, and means rotating oppositely with respect to said first mentioned rotating means and having a set of beater bars adapted to pass the adjacent edges of the respective first mentioned beater bars and to bend the material over said edges in the opposite direction, the peripheral speed of one of said sets of beater bars being greater than that of the other set, for the purpose specified. 15 75
- 20 23. In apparatus for treating fibrous material, the combination of means for holding the material, a stationary bar positioned ahead of said holding means over which the material may be fed, rotating means including a set of beater bars adapted to pass the adjacent edge of said bar, and to bend the material at certain places thereover in one direction, and means rotating oppositely with respect to said first mentioned rotating means and having a set of beater bars adapted to pass the adjacent edges of the respective first mentioned beater bars and to bend the material over said edges at substantially the same places in the opposite direction, the peripheral speed of one of said sets of beater bars being greater than that of the other set, for the purpose specified. 30 80
- 35 24. In apparatus for treating fibrous material, the combination of means for holding the material, a stationary bar positioned ahead of said holding means over which the material may be fed, rotating means including a set of beater bars arranged to pass the adjacent edge of said bar, and means rotating oppositely with respect to said first mentioned rotating means and having a plurality of beater bars adapted to pass the adjacent edges of the respective first mentioned beater bars, said stationary bar being so positioned relative to the path traveled by said first mentioned beater bars and said first and second mentioned beater bars being so arranged relative to each other that the free ends of said material are bent over the edge of said stationary bar in one direction through an angle substantially more than ninety degrees and then are bent over the edges of said respective first mentioned beater bars in the opposite direction at substantially the same places and through an angle substantially more than ninety degrees, the peripheral speed of one of said sets of beater bars being greater than that of the other set, for the purpose specified. 40 85
- 45 25. In apparatus for treating fibrous material, the combination of means for holding the material, a stationary bar positioned ahead of said holding means over which the material may be fed, rotating means including a set of beater bars adapted to pass the adjacent edge of said bar and to bend the material thereover in one direction, and means rotating oppositely with respect to said first mentioned rotating means but at the same speed and having a plurality of beater bars adapted to pass the adjacent edges of the respective first mentioned beater bars and to bend the material over said edges in the opposite direction, the radii of one of said rotating means being greater than those of the other rotating means, for the purpose specified. 50 90
- 55 26. In apparatus for treating fibrous material, the combination of means for holding the material, a stationary bar positioned ahead of said holding means over which the material may be fed, rotating means including a plurality of beater bars adapted to pass the adjacent edge of said bar and to bend the material thereover in one direction, and means rotating oppositely with respect to said first mentioned rotating means but at the same speed and having a plurality of beater bars adapted to pass the adjacent edges of the respective first mentioned beater bars and to bend the material over said edges in the opposite direction, the radii of one of said rotating means being greater than those of the other rotating means, for the purpose specified. 60 95
- 65 27. In apparatus for treating fibrous material, the combination of means for holding the material, a stationary bar positioned ahead of said holding means over which the material may be fed, rotating means including a plurality of beater bars adapted to pass the adjacent edge of said bar and to bend the material at certain places thereover in one direction, and means rotating oppositely with respect to said first mentioned rotating means but at the same speed and having a plurality of beater bars adapted to pass the adjacent edges of the respective first mentioned beater bars and to bend the material over said edges at substantially the same 100 105 110 115 120 125 130

places in the opposite direction, the radii of one of said rotating means being greater than those of the other rotating means, for the purpose specified.

- 5 28. In apparatus for treating fibrous material, the combination of means for holding the material, a stationary bar positioned ahead of said holding means over which the material may be fed, rotating means including a plurality of beater bars arranged to pass the adjacent edge of said bar, and means rotating oppositely with respect to said first mentioned rotating means but at the same speed and having a plurality of beater bars 10 adapted to pass the adjacent edges of the respective first mentioned beater bars, said stationary bar being so positioned relative to the path traveled by said first mentioned beater bars and said first and second mentioned beater bars being so arranged relative to each other that the free ends of said material are bent over the edge of said stationary bar in one direction through an angle substantially more than ninety degrees and 20 then are bent over the edges of said respective first mentioned beater bars in the opposite direction through an angle substantially more than ninety degrees, the radii of one of said rotating means being greater than those 25 of the other rotating means, for the purpose specified.

29. In apparatus for treating fibrous material, the combination of means for holding the material, a stationary bar positioned ahead of said holding means over which the material may be fed, rotating means including a plurality of beater bars arranged to pass the adjacent edge of said bar, and means rotating oppositely with respect to said first mentioned rotating means but at the same speed and having a plurality of beater bars adapted to pass the adjacent edges of the respective first mentioned beater bars, said stationary bar being so positioned relative to the path traveled by said first mentioned beater bars and said first and second mentioned beater bars being so arranged relative to each other that the free ends of said material at certain places are bent over the edge of said stationary bar in one direction through an angle substantially more than ninety degrees and then are bent over the edges of said respective first mentioned beater bars in the opposite direction 55 at substantially the same places and through an angle substantially more than ninety degrees, the radii of one of said rotating means being greater than those of the other rotating means, for the purpose specified.

30. In apparatus for treating fibrous material, the combination of a normally stationary means over which the material may be fed, rotating means including a plurality of beater means adapted to pass the adjacent edge of said stationary means and

to bend the material thereover at certain places in one direction, and means rotating oppositely with respect to said first mentioned rotating means and having a plurality of beater means adapted to pass relatively close to the adjacent edges of the respective first mentioned beater means and to bend the material over said edges in the opposite direction at substantially the same places, one of said first and second mentioned means being adjustable relatively to the other whereby the effect of the first mentioned beater means on the material being treated may be varied.

31. In apparatus for treating fibrous material, the combination of a normally stationary bar over which the material may be fed, rotating means including a plurality of beater bars adapted to pass the adjacent edge of said bar and to bend the material thereover in one direction, and means rotating oppositely with respect to said first mentioned rotating means and having a plurality of beater bars adapted to pass relatively close to the adjacent edges of the respective first mentioned beater bars and to bend the material over said edges in the opposite direction, said normally stationary bar and said second mentioned beater bars being adjustable relatively to said first mentioned beater bars whereby the effect of the two sets of beater bars on the material being treated may be varied.

32. In apparatus for treating fibrous material, the combination of a normally stationary bar over which the material may be fed, rotating means including a plurality of beater bars adapted to pass the adjacent edge of said bar and to bend the material thereover in one direction, said normally stationary bar being adjustable relatively to said beater bars, a shaft rotating oppositely with respect to said rotating means, driving means for said shaft, means carried by said shaft, and beater bars carried by said last mentioned means and adapted to pass relatively close to the adjacent edges of the respective first mentioned beater bars and to bend the material over said edges in the opposite direction, the means supporting said second mentioned beater bars being angularly adjustable relatively to said driving means, for the purpose specified.

33. In apparatus for treating fibrous material, the combination of a pair of rotating means each including a plurality of bars adapted to beat the material, and nozzles connected with a source of air supply and so positioned relative to said respective rotating means and the intended path of travel of the cleaned fiber through the apparatus that the vacuity produced by said rotating means is counteracted and the cleaned fiber is maintained in its said path.

34. In apparatus for treating fibrous material, the combination of a stationary bar over which the material may be fed, rotating means including a plurality of beater bars adapted to pass the adjacent edge of said bar and to bend the material thereover, means rotating oppositely with respect to said first mentioned rotating means and having a plurality of beater bars adapted to pass the adjacent edges of the respective first mentioned beater bars and to bend the material over said edges, and means for counteracting the vacuity produced by each of said rotating means and thereby to prevent the beaten material from winding therearound.
35. In apparatus for treating fibrous material, the combination of a stationary bar over which the material may be fed, rotating means including a plurality of beater bars adapted to pass the adjacent edge of said bar and to bend the material thereover, means rotating oppositely with respect to said first mentioned rotating means and having a plurality of beater bars adapted to pass the adjacent edges of the respective first mentioned beater bars and to bend the material over said edges, and pneumatic means associated with each of said rotating means and adapted to prevent the beaten material from winding therearound.
36. In apparatus for treating fibrous material, the combination of a stationary bar over which the material may be fed, rotating means including a plurality of beater bars adapted to pass the adjacent edge of said bar and to bend the material thereover, means rotating oppositely with respect to said first mentioned rotating means and having a plurality of beater bars adapted to pass the adjacent edges of the respective first mentioned beater bars and to bend the material over said edges, and a nozzle associated with each of said rotating means and connected with a source of air supply, said nozzles being so arranged relative to the respective rotating means that the vacuity produced by each of said rotating means is counteracted.
37. In apparatus for treating fibrous material, the combination of a frame, a roller journaled in said frame, a pair of arms pivotally connected at one end to said frame, a roller rotatably associated with said arms and co-operating with said first mentioned roller, and means whereby the other ends of said arms are normally drawn toward said first mentioned roller, for the purpose specified.
38. In apparatus for treating fibrous material, the combination of a frame, a roller journaled in said frame, a pair of arms pivotally connected at one end to said frame, a roller rotatably associated with said arms and co-operating with said first
39. In apparatus for treating fibrous material, the combination of a stationary bar, a pair of feed rollers adjacent one side of said bar, rotating means including a plurality of beater bars adapted to pass the other side of said stationary bar and to bend the material thereover at certain places in one direction, means rotating oppositely with respect to said first mentioned rotating means and having a plurality of beater bars adapted to pass relatively close to the adjacent edges of the respective first mentioned beater bars and to bend the material over said edges in the opposite direction at substantially the same places, and means to drive said rollers so that the material is fed over said stationary bar at a predetermined rate with respect to the rotative speeds of said respective rotating means, for the purpose specified.
40. In apparatus for treating fibrous material, the combination of a stationary bar, a pair of feed rollers adjacent one side of said bar, rotating means including a set of beater bars adapted to pass the other side of said stationary bar and to bend the material thereover in one direction, means rotating oppositely with respect to said first mentioned rotating means and having a set of beater bars adapted to pass the adjacent edges of the respective first mentioned beater bars and to bend the material over said edges in the opposite direction, and means to drive said rollers so that the material is fed over said stationary bar at a predetermined rate with respect to the rotative speeds of said respective rotating means, the peripheral speed of one of said sets of beater bars being greater than that of the other, for the purpose specified.
41. In apparatus for treating fibrous material, the combination of a stationary bar, a pair of feed rollers adjacent one side of said bar, rotating means including a plurality of beater bars adapted to pass the other side of said stationary bar and to bend the material thereover in one direction, means rotating oppositely with respect to said first mentioned rotating means but at the same speed and having a plurality of beater bars adapted to pass the adjacent edges of the respective first mentioned beater bars and to bend the material over said edges in the opposite direction, and means to drive said rollers so that the material is fed over said stationary bar at a predetermined rate with respect to the rotative speed of said respective rotating means, the radii of one of said rotating means being greater than those of the other rotating means, for the purpose specified.

42. In apparatus for treating fibrous material, the combination of a stationary bar, means adjacent one side of said bar for feeding the material to be treated thereover, 5 means adjacent the other side of the bar for bending the material over that side of the bar, and a bar floatingly supported over said first mentioned bar, for the purpose specified.
- 10 43. In apparatus for treating fibrous material, the combination of a frame, a stationary bar mounted on said frame, a roller journaled in said frame at one side of said bar, means adjacent the other side of said 15 bar for bending the material over that side of the bar, a pair of arms pivotally connected at their inner ends to said frame, a roller rotatably associated with said arms and co-operating with said first mentioned 20 roller, means adapted to draw the outer ends of said arms toward said first mentioned roller, a second pair of arms pivotally connected at their outer ends to said respective first mentioned arms, and a second bar positioned over said first mentioned bar and 25 connected to the inner ends of said second mentioned arms, for the purpose specified.
- 30 44. In apparatus for treating fibrous material, the combination of a stationary bar, means adjacent one side of said bar for feeding the material to be treated thereover, 35 rotating means including a plurality of beater bars adapted to pass the other side of said stationary bar and to bend the material thereover in one direction, means rotating oppositely with respect to said first mentioned rotating means and having a plurality of beater bars adapted to pass the adjacent edges of the respective first mentioned 40 beater bars and to bend the material over said edges in the opposite direction, and a
- bar floatingly supported over said stationary bar, for the purpose specified.
45. In apparatus for treating fibrous material, the combination of a stationary bar, 45 means adjacent one side of said bar for feeding the material to be treated thereover, rotating means including a set of beater bars adapted to pass the other side of said stationary bar and to bend the material there- 50 over in one direction, means rotating oppositely with respect to said first mentioned rotating means and having a set of beater bars adapted to pass the adjacent edges of the respective first mentioned beater bars and 55 to bend the material over said edges in the opposite direction, and a bar floatingly supported over said stationary bar, the peripheral speed of one of said sets of beater bars being greater than that of the other, 60 for the purpose specified.
- 65 46. In apparatus for treating fibrous material, the combination of a stationary bar, means adjacent one side of said bar for feeding the material to be treated thereover, 70 rotating means including a plurality of beater bars adapted to pass the other side of said stationary bar and to bend the material thereover in one direction, means rotating oppositely with respect to said first 75 mentioned rotating means but at the same speed and having a plurality of beater bars adapted to pass the adjacent edges of the respective first mentioned beater bars and to bend the material over said edges in the opposite direction, and a bar floatingly supported over said stationary bar, the radii of one of said rotating means being greater than those of the other rotating means, for the purpose specified.

JOHN N. SELVIG.

42. In apparatus for treating fibrous material, the combination of a stationary bar, means adjacent one side of said bar for feeding the material to be treated thereover, 5 means adjacent the other side of the bar for bending the material over that side of the bar, and a bar floatingly supported over said first mentioned bar, for the purpose specified.
- 10 43. In apparatus for treating fibrous material, the combination of a frame, a stationary bar mounted on said frame, a roller journaled in said frame at one side of said bar, means adjacent the other side of said 15 bar for bending the material over that side of the bar, a pair of arms pivotally connected at their inner ends to said frame, a roller rotatably associated with said arms and co-operating with said first mentioned 20 roller, means adapted to draw the outer ends of said arms toward said first mentioned roller, a second pair of arms pivotally connected at their outer ends to said respective first mentioned arms, and a second bar positioned over said first mentioned bar and connected to the inner ends of said second 25 mentioned arms, for the purpose specified.
- 30 44. In apparatus for treating fibrous material, the combination of a stationary bar, means adjacent one side of said bar for feeding the material to be treated thereover, 35 rotating means including a plurality of beater bars adapted to pass the other side of said stationary bar and to bend the material thereover in one direction, means rotating oppositely with respect to said first mentioned rotating means but at the same speed and having a plurality of beater bars adapted to pass the adjacent edges of the 40 respective first mentioned beater bars and to bend the material over said edges in the opposite direction, and a bar floatingly supported over said stationary bar, the radii of one of said rotating means being greater than those of the other rotating means, for the purpose specified.

bar floatingly supported over said stationary bar, for the purpose specified.

45. In apparatus for treating fibrous material, the combination of a stationary bar, 45 means adjacent one side of said bar for feeding the material to be treated thereover, rotating means including a set of beater bars adapted to pass the other side of said stationary bar and to bend the material thereover in one direction, means rotating oppositely with respect to said first mentioned rotating means and having a set of beater bars adapted to pass the adjacent edges of the respective first mentioned beater bars and 50 to bend the material over said edges in the opposite direction, and a bar floatingly supported over said stationary bar, the peripheral speed of one of said sets of beater bars being greater than that of the other, 55 for the purpose specified.

46. In apparatus for treating fibrous material, the combination of a stationary bar, means adjacent one side of said bar for feeding the material to be treated thereover, 60 rotating means including a plurality of beater bars adapted to pass the other side of said stationary bar and to bend the material thereover in one direction, means rotating oppositely with respect to said first 65 mentioned rotating means but at the same speed and having a plurality of beater bars adapted to pass the adjacent edges of the respective first mentioned beater bars and to bend the material over said edges in the 70 opposite direction, and a bar floatingly supported over said stationary bar, the radii of one of said rotating means being greater than those of the other rotating means, for the purpose specified.

JOHN N. SELVIG.

Certificate of Correction.

It is hereby certified that in Letters Patent No. 1,601,984, granted October 5, 1926, upon the application of John N. Selvig, of Chicago, Illinois, for an improvement in "Methods of and Apparatus for Treating Fibrous Material," errors appear in the printed specification requiring correction as follows: Page 8, line 87, claim 25, after the word "material" insert the words *at certain places*, and line 88, strike out the words "bent over the edge"; and that the said Letters Patent should be read with these corrections therein that the same may conform to the record of the case in the Patent Office.

Signed and sealed this 30th day of November, A. D. 1926.

[SEAL.]

M. J. MOORE,
Acting Commissioner of Patents.
